Primary Examiner — Cynthia M Chin(74) *Attorney, Agent, or Firm* — Smith Moore Leatherwood LLP; Thomas W. Epting(57) **CLAIM**

The ornamental design for a pot lid knob, as shown and described.

DESCRIPTION

FIG. 1 is a perspective view of our new pot lid knob;
 FIG. 2 is a rear elevational view of our new pot lid knob;
 FIG. 3 is a front elevational view of our new pot lid knob;
 FIG. 4 is a left side elevational view of our new pot lid knob;
 FIG. 5 is a right elevational view of our new pot lid knob;
 FIG. 6 is a top plan view of our new pot lid knob; and,
 FIG. 7 is a bottom plan view of our new pot lid knob.
 The broken lines shown are included for the purpose of illustrating the unclaimed portions of the article and form no part of the claimed design.
